CARL A. W. BRANDT, OF GREAT NECK, NEW YORK, ASSIGNOR TO THE SUPERHEATER COMPANY, OF NEW YORK, N. Y.

LOCOMOTIVE

Application filed January 19, 1925. Serial No. 3,538.

My invention relates to locomotive boilers and has for its general object the provision of a boiler having an evaporating and superheating capacity which is considerably greater per unit of length than is obtainable in boilers of present construction, and which also has a higher overall boiler efficiency than is obtainable with present types. Other and further objects will appear as the description proceeds.

The constant demand for locomotives of larger unit capacity resulted first in the development of locomotives to the maximum dimensions permitted by present road clearances, and further efficiency and capacity were then obtained by the addition of various boiler auxiliaries, among which is the fire tube superheater. In the earlier type of locomotives and in the majority now in use to which superheaters are applied, the comparatively small fire boxes and combustion chambers deliver the combustion gases to the fire tube section at a temperature very little below that of the fire box itself and with the high gas temperatures obtained in the fire tubes of the boiler, a comparatively small superheater is sufficient to give the desired degree of superheat. The advent of larger fire boxes and combustion chambers has increased boiler capacities and efficiencies by reducing the draft and cinder losses, and, by the absorption of greater quantities of radiant heat in the fire box section, reducing gas temperatures leaving the boiler. The advantages just described are, however, reduced to a considerable extent by the fact that the lower gas temperature in the fire tubes necessitates the use of a larger superheater surface in order to obtain the desired degree of superheat. To accommodate the larger superheater necessary to produce the desired superheat, and to handle the increased quantity of steam which this type of locomotive produces, it is necessary to greatly increase the number of large flues into which the superheater units are inserted and this construction materially reduces the total heating surface of the boiler. Furthermore, the fire tube superheater located in the flues of the boiler decreases to an ap-

preciable extent the free gas area through the boiler and consequently, its capacity. In addition the fire tube superheater limits the maximum thermal efficiency which may be obtained from a boiler, for in order to avoid a re-transfer of heat from the steam in the superheater to the combustion gases in the flues the gases in their passage through the latter must be maintained at a temperature above that of the superheated steam. Present practice requires steam temperatures of 600° F. or higher, and as a result the combustion gases must leave the flues at the uneconomically high temperature of 700° or 800° F. The presence of the fire tube superheater headers and connecting pipes in the smoke box end of the locomotive also precludes the possibility of allowing the combustion gases to pass from the fire tubes at a comparatively high temperature and thereafter abstracting from them their remaining useful heat by means of an economizer placed between the forward tube sheet and the stack.

My invention, therefore, contemplates the provision of a locomotive boiler of greater evaporating and superheating capacity per unit of length than has heretofore been obtained, and which also has a higher thermal efficiency, by the re-arrangement and redistribution of the various heating surfaces of the boiler. The manner in which these ends are obtained appears more fully in the following detailed description of specific embodiments of my invention, illustrated in the accompanying drawings in which:

Fig. 1 is a longitudinal vertical central section in a boiler constructed according to my invention;

Fig. 2 is a similar view on an enlarged scale of the forward end of the boiler shown in Fig. 1;

Fig. 3 is a transverse section taken on the line 3—3 of Fig. 2;

Fig. 4 is a fragmentary horizontal section, taken on the line 4—4 of Fig. 3;

Fig. 5 is a view similar to Fig. 1, of a modified form of boiler constructed according to my invention;

Fig. 6 is a transverse vertical section taken on the line 6—6 of Fig. 5;

Fig. 7 is a composite vertical transverse section, the left half of which is taken on the line 7^a—7^a of Fig. 1 and Fig. 5, and the right half of which is taken on the line 7^b—7^b of Fig. 1 and Fig. 5;

Fig. 8 is a view similar to Fig. 1 of another form of boiler constructed according to my invention;

Fig. 9 is a fragmentary plan view of a portion of Fig. 8;

Fig. 10 is a transverse vertical section taken on line 10—10 of Fig. 8, the superheater being removed for the sake of clarity;

Fig. 11 is an elevation of the settling tanks used in the forms shown in Figs. 1 and 8, and;

Fig. 12 is a vertical section through one of the individual tanks illustrated in Fig. 11.

Referring to the form shown in Fig. 1, my invention contemplates broadly the division of the heating surfaces of the boiler into four main units, so arranged that the flow of the combustion gases through them is counter to that of the water and steam, thereby, obtaining the most efficient heat transfer in accordance with the well known counter flow principle. The units of which the boiler is composed are substantially independent of each other in so far as the circulation of steam and water within the unit is concerned, and comprise a fire box unit, a superheater unit, a fire tube evaporating unit, and an economizer unit.

The fire box unit of my locomotive resembles a type which is in common use today, having two lateral water legs 1, and a rear water leg 2, with arch tubes 3 supporting the arch, or baffle 4, and with the top of the fire box being closed by the usual crown sheet 5. The fire box unit is extended forward of the arch 4 a considerable distance to form a combustion chamber 6 of large volume, and at the forward end the water space of the unit is closed by the sheet 7. Through the combustion chamber 6 and connecting the water space above the crown sheet with that below the floor of the combustion chamber extend the water tubes 8. As will be obvious, this form of fire box section, while similar in many respects to the conventional form of fire box, provides a much larger area of heating surface exposed to the direct radiant heat of the combustion gases, which are cooled to a greater extent than usual by the absorption of the radiant heat and leave the fire box at a temperature considerably below that at which they are discharged from the ordinary form of fire box. It is further to be noted that my fire box unit is of a size which permits complete combustion, before leaving the unit, of even the long flaming bituminous fuel which is generally used in railroad practice.

Upon leaving the firebox unit, the gases pass directly to the superheater unit, comprising a chamber 9 located between the sheet 7 and the tube sheet 10, and in which are located the tubular superheater elements to be described in detail later. By locating the superheater in this high temperature zone, I am enabled to obtain the required degree of superheat with a superheater having a much smaller area of heating surface and also a shorter path of steam travel than is required in the case of the firetube superheater. This results not only in a saving in space but also in a reduction of the pressure drop through the superheater over the firetube form. It is possible to place the superheater in the position noted, without injury to the superheating elements because of the fact that the large radiant heat absorbing surfaces of the firebox unit prevent the passage of gases to the superheater unit at an excessive temperature, and the tubes 8 form an efficient thermal screen between the superheater and the interior of the firebox unit.

By proper spacing of the water screen tubes 8 the superheater may be protected from excessive radiant heat, while at the same time a certain amount of radiant heat is allowed to penetrate to the superheater unit. By this arrangement I provide a superheater absorbing heat both by radiation and convection, which results in important advantages. A characteristic feature of the convection type superheater is the tendency to produce a low degree of superheat at low boiler ratings, with the superheat temperature rising as the boiler load increases. On the other hand, the radiant heat type of superheater tends to produce a more even degree of superheat, regardless of boiler load, but has other limitations which make its use in locomotive practice undesirable. By combining heat absorption both by radiation and convection I provide a superheater which will deliver steam at a more uniform temperature over the full range of boiler ratings than will the convection type, and avoid the defects inherent in the purely radiant heat type. It is also to be noted that the arrangement provided permits of great flexibility in design, as by varying the number of rows and the spacing of the tubes 8, the amount of radiant heat passing to the superheater unit may be controlled, and any superheat characteristics desired may be obtained in a given design.

Forward of the superheater unit, I provide the firetube evaporating unit composed of the tube sheets 10 and 11, the cylindrical sheet 12 forming the main barrel of the locomotive, and the firetubes 13. By this arrangement, the combustion gases, which have been considerably cooled by their passage through the firebox and superheater units, are brought into contact with evaporating

surfaces, the water side of which is not above the comparatively low temperature of the saturated steam. The rate of heat transfer in this unit, by convection from gases at a 5 moderate temperature, is much lower than that obtained in the firebox and superheater units, and in order to abstract the useful heat from the gases in this unit of the boiler a very large area of heating surface is desirable.

Furthermore, it is desirable to obtain through this, as well as all other portions of the boiler, the maximum free gas area, as experience and tests have shown that this latter factor is a direct measure of the capacity obtainable from a given size of boiler.

By my construction I am enabled to attain both of these desirable ends, as by the elimination of the firetube superheater, I am able to use a large number of small diameter fire-tubes instead of a smaller number of the large flues necessary to accommodate the elements of a firetube superheater, and, in addition, I have available a larger flue sheet area for the insertion of tubes than is the 25 case in the ordinary form of boiler. This latter advantage may be readily appreciated

from a consideration of Fig. 6 and 7. In the ordinary form of locomotive boiler the rear tube sheet form the forward end of the 30 firebox chamber and the size of the sheet is reduced by the water legs at either side of and below the firebox and the water space over the crown sheet. The maximum tube sheet area is therefore, in the ordinary form 35 of construction, limited to the cross sectional area of the forward end of the firebox, which is clearly shown as the space bridged by the tubes 8 in Fig. 7. In my construction the rear as well as the forward tube sheet has 40 an area equal to the full cross sectional area of the main barrel of the boiler, formed by the sheet 12 and, as illustrated in Fig. 6, this area, all of which below the water level is available for tubes, is manifestly consider- 45 ably greater than is available in the ordinary form of construction.

By the use of a large number of small diameter firetubes utilizing the full diameter of the boiler barrel, I obtain such a large 50 area of heating surface per unit of length that I am able to abstract the remaining heat from the combustion gases at a temperature useful for evaporating purposes, by an evaporating unit of comparatively 55 short length. This, together with the absence of the firetube superheater headers and the attendant piping, leaves, in a permissible over-all boiler length, a long and unobstructed smokebox 14 between the forward tube 60 sheet 11 and the combustion gas outlet 15, in which may be installed an economizer, or, if desired, a combustion air preheater, for the purpose of abstracting the remaining useful heat from the low temperature gases 65 leaving the firetube unit.

In one form, as illustrated on an enlarged scale in Fig. 2, I employ an economizer in this space made up of a series of cast sections placed in parallel relation to each other, and transversely of the smoke box, 70 each section comprising an upper header 16 and a lower one 17, the two headers being connected by a number of hollow bars 18 opening into the interior of the headers. These bars have, as more clearly appears from Fig. 4, a cross-shaped cross section and those of alternate sections are offset or staggered; those of each section extending beyond the limits of its header and to that extent overlapping and intermeshing with those of the adjacent section. The interior of the headers is suitably sub-divided by partitions 19 to give a zig-zag flow through each section, and the sections are suitably interconnected by nipples 20 (as shown in Fig. 9) to give a series flow through the economizer. Baffles 21 close the spaces between headers 16 and 17 and the sheet 12 and force the combustion gases to pass over the economizer sections on their way to the outlet 15.

In order to effect the maximum thermal efficiency, and also to prevent sweating of the economizer, with consequent corrosion, due to the introduction of cold feed water thereto, I prefer to preheat the feed water by means of an exhaust steam feed water heater 22 which may be mounted in front of the gas outlet 15, as shown in Fig. 1. The specific form of the feed water heater forms no part of the present invention, and need not be described in detail. Cold feed water from the boiler feed pump (not shown) passes through pipe 23 to the heater 22 and after being heated therein to substantially exhaust steam temperature passes to the economizer unit through pipe 24. The heater is supplied with exhaust steam from the engine cylinders (not shown) through pipe 25.

It is often necessary to supply locomotives with very impure feed water, the impurities consisting principally of sediment, and of carbonates and sulphates, in solution, which if allowed to enter the boiler or economizer precipitate and form scale upon the interior surfaces thereof and materially reduce their evaporating efficiency. I have therefore provided a simple and effective means whereby the elimination of sediment and scale forming matter is effected before its entry into either economizer or boiler. A number of vertical cylindrical tanks 26 are suitably mounted adjacent one side of the economizer, and a series of similar tanks 27 are mounted in the same manner on the opposite side, and as may be seen from Fig. 3, the main sheet 12 is so arranged at this point that the tanks 26 and 27 lie closely adjacent the economizer sections and do not protrude beyond the al-

lowable clearance limits of the locomotive.

Referring to Figs. 11 and 12, the construction and arrangement of tanks 26 is shown in detail. Each of the tanks 26 is provided with a conical member 28 open at its base and extending through the top of the tank, the several members 28 being connected to a common manifold 29 which is in turn connected to the pipe 24 leading from the feed water heater. A second manifold 30 is connected to the upper portion of each of the tanks 26, and at its other end is connected to the first economizer header 16, as clearly appears in Fig. 9. A blowoff manifold 31 is connected to the bottom of each of the tanks 26, and is fitted with the usual blowoff valve 32.

The construction and arrangement of tanks 27 is like that of tanks 26, except that the manifold 33 (Fig. 9) connecting the interior conical members is connected to the last header 16 of the economizer, and the manifold 34 connecting the upper portion of the tanks 27, leads through the connecting pipe 35 to the firetube evaporating section of the boiler. Tanks 27 are provided with a bottom blowoff manifold 36 and valve 37 (Fig. 3) in the same manner as tanks 26.

As previously noted, the temperature of the feed water in passing through heater 22 is raised to substantially exhaust steam temperature, which is sufficient to cause precipitation of the impurities it may contain in the form of carbonates. In this condition the feed water passes downwardly through the several conical members 28, the total sectional area of which is many times that of the pipe 24, and then upwardly through the still larger tanks 26. Because of the large flow area provided, the velocity of the feed water through members 28 and tanks 26 is very low, and ample opportunity is provided for the sediment and carbonate precipitates to settle to the bottom of the tanks 26, from which they may be blown off as desired, and the feed water then enters the economizer substantially free from sediment and carbonate impurities.

In passing through the economizer, the passages of which are serially connected, the feed water travels at a comparatively high velocity, and is heated ordinarily to a temperature of 300° F. or more. Impurities in the form of sulphates are precipitated at about this temperature, and immediately upon leaving the economizer the feed water enters the tanks 27, where these precipitates are allowed to settle out in the same manner as has been described in connection with the tanks 26, the purified feed water then entering the boiler through the connection 35.

In order to avoid complication, I prefer to have the economizer and feed water heater operate at boiler pressure, and for this reason I provide the settling chambers in the

form of a number of cylindrical tanks connected in parallel, as this means enables me to secure the necessary large flow area with apparatus which may be cheaply and easily constructed from standard materials, and which will also easily withstand boiler pressures.

Referring again to Fig. 1, it may readily be seen that the firebox and fire tube units of the boiler are independent of each other in so far as circulation connections are concerned, and in order to supply water to the firebox unit and also to equalize the water levels in the two units, I provide the connecting pipe 38, which forms the sole connection between the two units below the water level thereof. A flexible expansion joint 39 is provided in the pipe 38 to take care of any stresses which may be set up therein. It is to be understood, however, that this connection between the two units need not be limited to a single pipe, but may be effected by a plurality of similar connections.

It is further to be noted that the steam spaces of the firebox unit and the fire tube unit are separate. The steam liberated in the firebox unit is taken off from the steam dome 40 by the steam pipe 41, while that formed in the fire tube unit is taken off from the steam dome 42 by the steam pipe 43. The steam offtake pipes 41 and 43 connect respectively with the superheater headers 44 and 45, which are respectively connected by tubular superheater elements 46 and 47 to a common outlet header 48, to the flanged outlet of which is secured the throttle housing 49.

The superheater elements 46 and 47 are made up of loops, the ends of which are secured in any desired manner to the headers, with the loops providing the possibility of movement of the several headers relative to each other, which is necessary on account of the rigid attachment of the headers 44 and 45 to their respective steam domes. The headers, it will be noted, are out of the direct line of the gas travel and the connections between them and the superheater elements are thus protected from extreme temperature conditions.

Referring now to Figs. 5 and 6, I have shown a slightly different form of boiler, in which the firebox and superheater units are constructed and arranged in the same manner as in the form shown in Fig. 1, and in which the fire tube unit is modified to accommodate a different type of economizer. In this form the fire tubes are longer than in the form shown in Fig. 1 and the forward ends of the central tubes are enlarged, as at 13', to accommodate the economizer elements, which are of the tubular return bend type commonly used in firetube superheaters. In this form the economizer comprises an upper transverse drum 50 and a lower simi-

70

100

105

110

115

120

125

130

lar drum 51, the two drums serving as headers which are connected by a plurality of economizing elements 42. Drums 50 and 51 are divided by partitions 53 to give a suitable series parallel flow through the economizer from the inlet pipe 24' leading from the heater 22, to the outlet pipe 35', which delivers the feed water to the boiler. As in the form shown in Fig. 1, the feed water receives its initial heat in the heater 22. It then passes serially through the drums 50 and 51 and the elements 52 to the boiler. Because of the large diameter of drums 50 and 51, the velocity of the feed water passing through them is very low, and the sediment and precipitates formed by the heating both in the preheater and the economizer have ample opportunity to settle out in the drums, from which they may be blown off through the blowoff connections 54.

It is to be noted that this form of economizer is not open to the objections applicable to a superheater in this location, as the temperature to which the water must be heated is much below that required for the steam, and a much smaller sectional flow area of economizer is required than is required in a superheater. Consequently, with an economizer in this position, the combustion gases may still be reduced to an economically low temperature in the fire tubes, and the sectional area of the economizer does not cause a serious diminution in the free gas area through the tubes, as is the case with a superheater. The slight loss in heating surface per unit length in the fire tube section due to the enlargement of the tubes (which need not be so large as those necessary to accommodate a superheater) is compensated for by the fact that the firetubes may be made longer than in the case where an economizer of the type shown in Fig. 1 is employed.

In Figs. 8 to 10 I have shown a third form of boiler which in the general arrangement of the units is similar to that shown in Fig. 1, but in which the form of water and steam connections between the firebox and the firetube units has been modified. In some forms of locomotives, the proximity of the running gear to the under side of the boiler shell makes the use of the outside connecting pipe or pipes 38 undesirable and in such cases I provide an internal connection between the two sections below the water level thereof, which functions in the same manner as the external connection. In this form the main cylindrical sheet is belled out on the lower side of the boiler, as at 12', and a tapered semi-cylindrical sheet 55 is provided inside the main sheet, connecting the inner water leg walls of the firebox unit with the rear tube sheet of the firetube unit. Above the horizontal diameter of the boiler

the sheet 55 is carried vertically upward until it meets the main boiler sheet, to which it is suitably secured along the line indicated at 55' in Fig. 8. The space between the sheet 55 and the main boiler shell provides a water passage 56 connecting the firebox with the firetube unit, and it is to be noted that the passage 56 is closed by the juncture of the two sheets at a point below the water level in the boiler, so that there is no interior communication between the steam spaces of the firebox and firetube units. As may be seen from Fig. 8, the main boiler shell is belled, and the sheet 55 tapered, in order that the rear tube sheet 10' may be made as large as the forward tube sheet, and the maximum number of fire tubes employed.

In the boiler shown in Fig. 8 I have also shown a modified form of steam offtake. According to this arrangement, the steam domes on the firebox and fire tube units may be omitted, and the steam liberated in the firebox section, instead of being delivered directly to the superheater, is carried by means of one or more conduits 57 to the steam space of the firetube unit, these conduits forming the only connection between the two steam spaces. Steam from both units is carried to the superheater by the conduit 58, which connects the forward end of the steam space of the fire tube unit with the superheater inlet header 59, and in which may be placed the steam separator 60. The header 59 is in the form of a Y, the branches of which embrace the outlet header 49', and to which they are connected by the tubular superheater elements 46' and 47'. Header 48' connects, through the throttle 49', with the conduit 61 leading to the engine cylinders.

It will thus be seen that without departing from the usual exterior form of locomotive boiler, which enables me to mount the customary boiler auxiliaries in the ordinary manner, and without employing any structure which cannot be cheaply and easily fabricated with existing shop equipment, I have provided a locomotive boiler possessing many advantages over prior forms, which may be briefly summarized as follows:

The extremely large firebox unit, possible because of the short fire tube unit, enables me to use large grates, thereby reducing the draft and cinder losses in the boiler, and the large area exposed to radiant heat in this section enables me to make use to the fullest extent of the rapid rate of heat transfer by radiation.

The firebox unit should be primarily a steam producing unit, and in my construction this characteristic is assured by the fact that no water reaches the firebox unit until it has first been brought to the evaporating

temperature, by passage through the fire tube unit, which is at evaporating temperature and producing steam. In this connection it is to be noted that the firebox unit is by far the greater steam producer of the two units, and the rate of evaporation in this unit is very high. As a consequence, large quantities of water are required by this unit, which is moreover sensitive to changes in steam demand and the rate of firing, and the varying demand for water in the firebox unit is readily met by the large reserve of water at evaporating temperature in the fire-tube unit. With evaporation taking place much more rapidly in the firebox unit than in the firetube unit, the flow of water through either the external or internal connections between these two units is always from the latter to the former, and the circulation of water within one individual unit is independent of that in the other.

By my arrangement of units, I assure a supply of water to the firebox unit that is substantially pure and free from scale forming impurities, as the firetube unit provides a reservoir of comparatively slow moving water in which any residue of impurities, which may not have settled out in the chambers provided for the purpose, may be precipitated. This is of advantage not only because of the fact that impurities may be removed more easily from the fire tube unit than from the firebox unit, but also because evaporating surfaces of the fire tube unit, being exposed only to gases which have been cooled by passage through the firebox and superheater units, are not so likely to be injured by overheating due to scale accumulations on their inner surfaces as are the evaporating surfaces of the firebox unit, which are directly exposed to the intense temperatures of the furnace and combustion chamber.

I provide for a considerably increased free gas area through the boiler without an increase in its diameter, because of the removal of the superheater from the firetubes, thus permitting the use of small diameter tubes, and the provision of tube sheets which extend across the full diameter of the boiler shell. This increase in free gas area may amount to as much as twenty-five or thirty per cent. By the removal of the superheater from the discharge end of the firetubes, I am enabled to reduce the gas temperature at this point to a degree approaching that of the boiler temperature without in any way affecting the degree of superheat obtained, and because of the free space available at the smoke box end of the boiler, I am able to utilize an economizer which will reduce the flue gas temperature to a still lower degree before its discharge through the stack. By this arrangement of the various units of the boiler, I utilize to the fullest possible extent

the counterflow principle of heating and am able to reduce the gas temperature at the boiler outlet to the lowest possible degree, without impairing the efficiency of any unit in the boiler, and with the use of the minimum area of heating surface, for a given amount of evaporation.

I provide a superheater which, with the minimum amount of heating surface, is capable of producing high degrees of superheat, which also has the large steam flow area necessary to handle the steam requirements for a large locomotive without causing objectionable pressure drop, and which at the same time does not restrict the free gas area through the boiler. The superheater is furthermore so located as to be readily accessible for inspection and repair, and by disconnecting the steam connections may easily be removed by an overhead crane, through the top of the boiler shell, for overhauling or replacement. Furthermore, the superheater chamber 9, which may be entered through suitable removable cover plates in the main boiler shell, provides space from which the rear tube sheet may be inspected and repaired.

In the forms shown in Figs. 1 and 5, an important advantage is gained in the protection of the superheater elements during firing up periods by a flow of steam therethrough. As will be noted, the connections through the superheater form the only communication between the steam spaces of the firebox and firetube units, and as the former produces steam much more rapidly than the latter, a considerable flow of steam will take place from the firebox to the firetube unit, through the superheater, to equalize the pressure between the two units. This steam flow acts as a protection for the superheater elements against overheating during the firing period, when the throttle is closed, and there is no normal flow of steam through the superheater.

In the form shown in Fig. 8, the additional superheater protection just described has been omitted and a steam piping arrangement has been provided which will insure dry steam entering the superheater even under the most severe operating conditions tending to produce boiler foaming or priming. In this case, the steam being taken off from the firebox section, where there is the most violent ebullition does not pass directly to the superheater, but through the conduits 57 to the steam space of the comparatively quiet fire tube section from whence it is taken to the superheater through the conduit 58, which is connected to the steam space of the fire tube unit at the forward end thereof, where there is comparatively little steam generation to cause disturbance, and where the entrance of the feed water from the economizer fur-

ther tends to produce a quiet zone suitable for dry steam removal.

As an additional precaution, the steam separator 60 may be inserted in the conduit 58, and in the forms shown in Figs. 1 and 5, steam separators of any well known type may be installed in the steam domes, but as the specific form of such separators form no part of the present invention, they have for the sake of clearness been omitted from the figures.

What I claim is:

1. In a locomotive boiler, in combination, a fire-box unit forming a furnace and combustion chamber in which combustion is substantially completed and having a combustion gas outlet substantially coextensive with the cross-sectional area of said chamber, a plurality of rows of vertical water tubes 20 joining opposite water spaces of said unit adjacent said outlet, said tubes being spaced to permit a portion of the radiant heat generated in said chamber to pass through said outlet; a superheater unit over which the 25 combustion gases pass located adjacent and extending across substantially the entire area of said outlet; a fire tube evaporating unit located forwardly of said superheater and comprising a plurality of closely spaced 30 small diameter tubes distributed over the entire cross-sectional area of the boiler below the water level thereof, whereby maximum heating surface is obtained in the fire tube unit with minimum tube length, a long unob- 35 structed smoke-box located forwardly of said fire tube unit, an economizer located in said smoke-box, a feed water heater, conduits for 40 delivering feed-water through the economizer from the feed-water heater to the fire tube unit, means connecting the water spaces of the fire tube unit and the firebox unit, and means for delivering steam generated in said units to the superheater.

2. A locomotive boiler formed by a fire 45 box unit, said unit comprising a locomotive type furnace having substantially greater length than width, baffling means in said furnace for causing the major portion of the combustion gases generated therein to make at least two passes through said furnace, a combustion chamber extending rearwardly of the furnace and terminating in an outlet substantially co-extensive with the sectional area of the chamber, and a plurality of water 55 tubes joining the top and bottom water spaces of said unit adjacent said outlet, said tubes being spaced to permit a portion of the radiant heat generated in said chamber to pass through said outlet; a superheater over 60 which the combustion gases pass located adjacent and extending across substantially the entire area of said outlet whereby it is exposed to direct radiation from said chamber, a fire tube evaporating unit through 65 which the combustion gases pass after leav-

ing said superheater, an economizer located forwardly of said fire tube unit and through which the combustion gases pass after leaving said unit, means connecting the water spaces of said units and means for delivering steam generated in said units to the super- 70 heater.

3. A locomotive boiler formed by a fire box unit, said unit comprising a locomotive type furnace having substantially greater length than width, arch tubes extending over said furnace, a baffle supported by said tubes and extending forwardly from the rear ends thereof to form the furnace roof, a long combustion chamber extending rearwardly of said baffle and terminating in an outlet substantially coextensive with the sectional area of the chamber, and a plurality of water tubes joining the top and bottom water spaces of said unit adjacent said outlet, said tubes being spaced to permit a portion of the radiant heat generated in said chamber to pass through said outlet; a superheater over which the combustion gases pass located adjacent and extending across substantially 80 the entire area of said outlet, whereby it is exposed to direct radiation from said chamber, a fire tube evaporating unit through which the combustion gases pass after leaving said superheater, an economizer located 85 forwardly of said fire tube unit and through which the combustion gases pass after leaving said unit, means connecting the water spaces of said units, and means for delivering steam generated in said units to the 90 superheater.

4. In a locomotive boiler, in combination, a firebox evaporating unit, a second evaporating unit spaced therefrom, and through which the combustion gases flow after leaving said fire box unit, means connecting said units below the water level thereof, and a superheater located in the space between said units, said superheater providing the sole communication between the steam spaces of 100 said units.

5. In a locomotive boiler, in combination, a firebox evaporating unit, a second evaporating unit spaced therefrom, and through which the combustion gases flow after leaving said fire box unit, means connecting said units below the water level thereof, and a superheater located in the space between said units, said superheater forming a flexible connection between the steam spaces of 110 said units.

6. In a locomotive boiler, in combination, a firebox evaporating unit, a second evaporating unit spaced therefrom and through which the combustion gases flow after leaving said fire box unit, means connecting said units below the water level thereof, and a superheater located in the space between said units, said superheater comprising two 125 inlet headers, a single outlet header, a plu- 130

rality of superheater elements connecting said headers, and means connecting each of said units to a single inlet header.

7. In a locomotive boiler, an evaporating unit terminating in a forward tube sheet, a main shell forming a part of said unit and extending forwardly therefrom to form a smoke box section having a combustion gas outlet, an economizer located in said smoke box section intermediate said tube sheet and outlet, said economizer comprising a plurality of serially connected sections set transversely of said smoke box and occupying the full rectangular cross section thereof, and baffles closing the spaces between said shell and economizer, whereby all the combustion gases are forced through the latter.

8. The combination as set forth in claim 7; the individual sections being integrally cast and comprising top and bottom headers, hollow bars connecting said headers, and partitions in said headers whereby a serial flow is obtained through said sections from the inlet to the outlet thereof.

9. The combination as set forth in claim 7; said sections comprising a plurality of hollow cross-shaped bars forming water passages through said sections, the bars of adjacent sections being staggered with respect to the direction of gas flow therethrough, whereby a zig zag gas flow is produced.

10. The combination as set forth in claim 7; said sections comprising top and bottom headers connected by vertical hollow cross shaped bars; the bars of adjacent sections being staggered with respect to the gas flow with the extending arms of the bars of adjacent sections in over-lapping and intermeshing relation.

11. In a locomotive boiler, the combination of an evaporating unit, a feed water heater and an economizer, means for delivering feed water to the evaporating unit through the feed water heater and the economizer serially in the order named, said means including a primary settling space between the feed water heater and the economizer, a secondary settling space between the economizer and the evaporating unit, and means for removing the impurities deposited in said spaces.

12. In a locomotive boiler, the combination of an evaporating unit heated by combustion gases, a feed water heater in which the feed water for said unit is heated by exhaust steam from the locomotive engine to substantially exhaust steam temperature whereby the precipitation of some of the impurities in the feed water is effected, an economizer in which the feed water is heated by the combustion gases to substantially evaporating temperature at boiler pressure whereby the remaining impurities in the feed water are precipitated, a conduit con-

necting the feed water heater and the economizer, means forming a primary settling space in said conduit in which the impurities precipitated in the feed water heater are deposited, a second conduit connecting the economizer and the evaporating unit, means forming a secondary settling space in said second conduit in which the impurities precipitated in the economizer are deposited, and means for removing the impurities deposited in said spaces.

13. In a locomotive boiler; the combination with a fire tube evaporating unit and the main boiler shell extending forwardly therefrom to form a smokebox section; of an economizer located within said smokebox section and delivering feed water to said fire tube unit, a feed water heater, a connection from said feed water heater to said economizer, means adjacent said economizer forming a primary settling space in said connection, a connection from said economizer to said fire tube unit, and means located adjacent said economizer forming a secondary settling space in said last named connection.

14. In a locomotive boiler, in combination, a fire tube evaporating unit, a main boiler shell, extending forwardly therefrom and forming a smoke box section, an economizer located within said smoke-box section and occupying the full rectangular cross section thereof, a feed water heater settling chambers at either side of said economizer, said main boiler shell being constructed and arranged adjacent said economizer to permit said settling chambers to lie closely adjacent said economizer and at least in part within the circular outline of said boiler shell, and means forming a feed water path from said feed heater to said fire tube unit, said means including said economizer and said settling chambers, said economizer being disposed in said path intermediate the settling chambers at either side thereof.

15. In a locomotive boiler, in combination, a fire tube evaporating unit, a main cylindrical boiler shell extending forwardly therefrom and forming a smoke-box section, said shell having flat portions along the sides thereof, an economizer located in said smoke-box section occupying substantially the entire space between said flat portions of said shell, a series of vertical settling tanks mounted in the recess formed by the flat portion on one side of said shell adjacent said economizer, a second series of vertical settling tanks mounted in the corresponding recess on the other side of said economizer, a feed water connection leading through each of said first series of settling tanks to said economizer, and a feed water connection leading from said economizer through each of said second series of settling tanks to said fire tube unit.

16. In a locomotive boiler, in combination, a fire box evaporating unit having a combustion gas outlet with water spaces above and below said outlet, a plurality of rows of vertical water tubes connecting said water spaces and extending across said outlet; a fire tube evaporating unit spaced forwardly from said fire box unit and comprising a plurality of fire tubes distributed over the entire cross-sectional area of the boiler below the water level thereof; a superheater unit located in the space between said first-named units and comprising a pair of inlet headers and an outlet header, and a plurality of vertical return loop superheater elements connecting each of said inlet headers with said outlet header, all of said headers being located above the level of said fire tubes and said upper water space; a baffle bridging the space between said fire box unit and said fire tube unit below said headers, means connecting the water spaces of said evaporating units, and means for delivering steam generated in said evaporating units to said inlet headers.
17. In a locomotive boiler, in combination, a fire-box unit forming a furnace and combustion chamber in which combustion is substantially completed and having a combustion gas outlet substantially coextensive with the cross-sectional area of said chamber, a plurality of rows of vertical water tubes joining opposite water spaces of said unit adjacent said outlet, said tubes being spaced to permit a portion of the radiant heat generated in said chamber to pass through said outlet; a superheater unit over which the combustion gases pass located adjacent and extending across substantially the entire area of said outlet; a fire-tube evaporating unit located forwardly of said superheater and comprising a plurality of closely spaced small diameter tubes distributed over the entire cross-sectional area of the boiler below the water level thereof, whereby maximum heating surface is obtained in the fire tube unit with minimum tube length, a long unobstructed smoke-box located forwardly of said fire tube unit, a feed water heater, an economizer located in said smoke-box, and means for delivering all of the water fed to the fire-box section through the feed water heater, economizer and fire tube section serially in the order named.
